(57) **CLAIM**

We claim the ornamental design for a hanger for clothing care machine, as shown and described.

DESCRIPTION

FIG. 1 is a perspective view of a hanger for clothing care machine showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front view thereof shown in a state of use.

The broken lines in FIGS. 3 and 7 depict portions of the hanger for clothing care machine that form no part of the claimed design. The broken lines in FIG. 8 depict an environmental clothing care machine that forms no part of the claimed design.

1 Claim, 8 Drawing Sheets
